UNITED STATES PATENT OFFICE.

ELI J. BEAUPRE, OF NORTH ATTLEBORO, MASSACHUSETTS.

CIGARETTE CASING.

Application filed December 5, 1923. Serial No. 678,608.

To all whom it may concern:

Be it known that I, ELI J. BEAUPRE, a citizen of the United States, residing at North Attleboro, in the county of Bristol and State 5 of Massachusetts, have invented certain new and useful Improvements in Cigarette Casings, of which the following is a specification.

This invention relates to improvements in 10 the construction of casing for carrying small articles, the same being designed more particularly for use in receiving a pack of cigarettes; and the object of this invention is to provide a neat construction of receptacle which is substantially in the form 15 or shape of a pack of cigarettes, the same being provided with a lid hinged at one side thereof which side may be opened for the reception of a full pack of cigarettes.

20 A further object of the invention is the provision of a casing of this character having a lid formed in trough shape and adapted to receive one or more cigarettes for presentation when swung back to open position.

25 A still further object of this invention is the constructing of the lid that it may also serve as an ash-tray when swung to open position.

30 With these and other objects in view, the invention consists of certain novel features of construction, as will be more fully described, and particularly pointed out in the appended claims.

35 In the accompanying drawings:

Figure 1 is a perspective view of a casing showing the lid closed.

40 Figure 2 is a perspective view of the casing showing the lid open and a pack of cigarettes therein.

Figure 3 is a perspective view showing a strip of metal bent into U-shape to form the front and rear and also the side walls of the body member.

45 Figure 4 is a perspective view showing one of the end wall members detached.

Figure 5 is a perspective view showing the inner side of the lid member detached.

50 Figure 6 is a perspective view showing the hinge pintle formed of flat wire adapted to serve as a torsional opening spring for the lid.

Figure 7 is a perspective view illustrating 55 the casing with its lid swung to open position and resting upon a base to serve as an ash tray.

It is found in the use of casings for carrying a pack of cigarettes, of advantage to form the same with rounding edges to closely fit the pack so as to take up the 60 minimum amount of space; also to provide a casing which is open at one side instead of at its end to permit the pack which is provided with rounded sides to readily enter the side opening of the casing. It is also 65 found of advantage to provide the body of the casing of a width less than that of the pack and to form one of the end walls of the casing of a height less than the width of the pack whereby as illustrated in Figure 70 2, a portion of the pack extends above this end wall so that when the wrapper is torn away the ends of the cigarettes will be exposed and be readily accessible for presentation. It is also found of advantage to form 75 the lid or cover of U-shape in cross section to fit over the extending side of the pack and to provide one end of the lid with a wall of a depth to cooperate with the end wall of the body to close the opening to the body 80 when the lid is shut.

Also by providing a structure of this character the lid may serve a double purpose: First, it may serve as an ash tray as illustrated in Figure 7, or as a cigarette receptacle into which some of the loose cigarettes 85 may be deposited for presentation when the side of the wrapper is torn away and in which case the open end of the lid performs the useful function of permitting the cigarettes to be extended beyond its edge for ready presentation; and the following is a detailed description of one construction by which these several advantageous results 90 may be obtained:—

With reference to the drawings, 10 designates a strip of sheet material preferably metal, which is bent into U-shape forming front and rear walls of the casing body. The edge of the rear wall being provided 100 with extending portions which are bent into loop form to provide hinge members 11.

End walls 12 and 13 are secured to this body portion preferably by rolling the edges of one over those of the other or these end walls may be soldered in position, if desired. One of the end walls 12 is preferably formed longer than the wall 13, the wall 12 extending beyond the edge of the body and in addition to serving as a closure for that end it 110 also serves as a rest or support for a portion of the bottom of the pack. The edge of wall

13 is preferably cut downwardly on a circle as at 14 to permit one or more of the cigarettes 15 of the pack to be advanced endways to project beyond its wall for ready presentation when a portion of the pack wrapper is torn away as at 16. The lid member 17 is also of U-shape in cross section, one end being provided with an end wall 18 rounded as at 19 to fit the concaved edge 14 of the end wall 13 when the lid is closed while the opposite end of this lid is preferably left open as at 20 to fit around the extending edge 21 of the end wall 12.

A latch 22 is formed on the inner surface 15 of the lid 17 and is adapted to snap into the opening 23 in the lip 22 which is fastened onto the front wall of the casing whereby it is only necessary to press the guiding edge of this front wall inwardly to release the pin 26 permitting the lid to swing to open position under tension of the torsional pintle spring 25. By my improved construction the lid when in open position may serve as an ash tray as illustrated in Figure 7, or in 20 other cases when the projecting edge of the wrapper is torn away the full length of a cigarette thus exposed may be dropped into the lid and then carried endwise to extend beyond the opening end thereof for ready 25 presentation.

By my improved construction of box which is opened on one side instead of at the end the pack which is round on its side edges very readily enters this casing 35 and as the width of the body of the casing is less than that of the pack, the pack may be readily positioned in the casing and as readily removed when desired.

The trough shape of the lid lends itself 40 to being swung into position over the extending edge portion of the pack thereby causing its end wall 18 to cooperate with the wall 13 of the body to close this end of the pack walls the open end of the lid which 45 fits around the projecting end 12 of the opposite end wall also closes that end of the casing.

My improved casing is very simple and practical in construction and when the lid 50 is open serves a number of useful purposes as a smoker's article.

I do not wish to be limited to using the casing for cigarettes as the same may be used as a casing for any article which it is adapted to carry.

The foregoing description is directed solely towards the construction illustrated, but I desire it to be understood that I reserve the privilege of resorting to all the mechanical changes to which the device is 55 susceptible, the invention being defined and limited only by the terms of the appended claims.

I claim:

1. A sheet metal casing for cigarettes comprising a body member of a strip of sheet metal folded into U-shape in cross section forming front, bottom and back walls substantially the length of a cigarette, walls at the end of said body, and a cover hinged 65 to said body and having a portion of one of the end walls attached thereto to expose the end of a cigarette when open.

2. A cigarette casing comprising a body closed at its ends by walls and open on one 70 side to edgeways receive a pack of cigarettes, the width of the body being less than that of a cigarette pack, one of said end walls being shorter than the other the longer wall 75 projecting above the open edge of the front and rear walls to support one end of the pack, a lid U-shaped in cross section hinged to one edge of the body and having one end wall adapted to cooperate with the shorter body wall to close the casing when 80 the lid is shut.

3. A sheet metal casing for cigarettes comprising a body member U-shaped in cross section, a wall at one end of said body extending above the front and back walls 90 thereof, a cover member hinged to said body shaped to fit over said extended end wall, a wall at the other end of said body divided into complementary portions, one portion carried by the body and cut out 95 below the upper edge of the front and rear walls thereof and the other complementary portion of said end wall being carried by said cover whereby the cover with its end wall is adapted to close the box.

In testimony whereof I affix my signature.
ELI J. BEAUPRE
